UNITED STATES PATENT OFFICE.

JOHN STEVENS ORR, OF AUGUSTA, KENTUCKY.

SHOE.

1,210,521.

Specification of Letters Patent. Patented Jan. 2, 1917.

Application filed September 23, 1915. Serial No. 52,241.

To all whom it may concern:

Be it known that I, JOHN S. ORR, a citizen of the United States, residing at Augusta, in the county of Bracken and State 5 of Kentucky, have invented a new and useful Shoe, of which the following is a specification:

The device forming the subject matter of this application is a protector adapted to be 10 applied to a shoe or boot for the purpose of shielding the same against wear and for the further purpose of providing an anti-slipping surface.

The invention aims to provide a structure 15 of this sort which may be assembled readily with shoes of different sizes, the construction being such that the protector will remain firmly assembled with the article of footwear.

It is within the province of the disclosure 20 to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed, without departing from the spirit of the invention.

In the accompanying drawing:—Figure 1 35 shows in fragmental side elevation, an article of footwear whereto the device forming the subject matter of this application has been applied; Fig. 2 shows the invention in bottom plan, applied to a shoe; Fig. 3 is 40 a cross section on the line 3—3 of Fig. 2; Fig. 4 is a top plan of the protector detached from the shoe.

In the accompanying drawings, the numeral 1 indicates the main sole of a shoe 2. 45

The protector forming the subject matter of this application preferably is fashioned from metal throughout saving as herein-after specified, and embraces a pair of toe plates 3 overlapped at their forward ends 50 as shown at 4, the overlapped ends of the toe plates 3 being united by a pivot element preferably in the form of a rivet 5. Overlapped upon the rear ends of the toe plates 3 are auxiliary plates 6 united with the rear

ends of the toe plates 3 by means of pivot 55 elements which may be rivets 7. The plates 3 and 6 are provided with upright flanges 8 adapted to engage the edges of the main sole 1, the flanges 8 terminating in lips 9 disposed parallel to the respective plates 3 and 60 6 and adapted to overhang and engage the upper face of the protruding edge of the sole 1. As indicated at 10, the auxiliary plates 4 and 6 turn upwardly as they extend rearwardly so as to coöperate properly with 65 the upward curve of the sole 1 as the latter extends toward the heel 16 of the shoe.

If desired, but not of necessity, an auxiliary sole 11 may be interposed between the main sole 1 and the plates 3 and 6. This 70 auxiliary sole 11 preferably is fashioned from leather but any other substance, such as metal, may be employed if desired. The toe plates 3 may be roughened as shown at 12 or constructed in any desired manner, so 75 as to present an anti-slipping surface. The rivets 5 and 7 preferably are tightened down sufficiently so that the relative movement between the constituent parts of the protector may be brought about only with 80 considerable difficulty. As a consequence, when the protector is assembled with a shoe, as shown in Figs. 1 and 2, no additional means, ordinarily, is required for holding the protector in place. After a time, however, 85 the rivets 5 and 7 may become somewhat loose, under which circumstances it may be desirable to nail the protector to the sole of the shoe. With this end in view, the toe plates 3 are equipped with any desired number of 90 openings 14, of any size, and positioned as may be required, the auxiliary plates 6 of the protector being provided with openings 15, the openings 14 and 15 being adapted, in an obvious manner, to receive nails or 95 other securing elements whereby the protector and the sole 11, if the latter be used, may be attached to the main sole 1 of the shoe.

It is to be observed that the protector 100 forming the subject matter of this application is so constituted that it may be adjusted readily to accommodate articles of footwear of different sizes. The main sole of the article of footwear will be adequately 105 protected, and, at the same time, an anti-slipping surface will be presented.

The structure forming the subject matter

of this application will greatly lengthen the life of articles of footwear by covering and shielding the soles thereof.

Having thus described the invention, 5 what is claimed is:

In a device of the class described, a pair of forward plates adapted to be applied to the sole of a shoe and of sufficient length to extend unbrokenly from the toe of a shoe 10 to the intermediate portion of the ball thereof, the forward ends of the plates being curved toward each other and being overlapped, the inner edges of the plates being spaced apart to the rear of the forward 15 ends of the plates; a pivot element uniting the overlapped forward ends of the plates; and a pair of rear plates the forward ends of which are overlapped upon the rear ends of the forward plates and pivoted thereto 20 for lateral swinging movement, the rear

ends of the rear plates being free; all of the plates having upstanding flanges provided with inwardly projecting sole-engaging lips, the flanges and the lips on the forward plates being spaced from the flanges 25 and the lips on the rear plates, adjacent the points or pivotal connection between the rear plates and the forward plates, to permit lateral swinging movement of the rear plates, and to permit a vertical bending, in 30 conformity to the bending of the sole wherever the structure is assembled.

In testimony that I claim the foregoing as my own, I have hereto affixed my signature in the presence of two witnesses.

JOHN STEVENS ORR.
